ABSTRACT

Matched video variable gain amplifiers having dynamic resistances coupled to the input and output circuits thereof and having reciprocal logarithmic responses so that the output of a video servo loop can be nulled.

FIG. 3.

CONTROL CONVERTER AMPLIFIERS

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

The invention comprises an improvement in a servo loop comprising the incorporation of variable gain amplifiers wherein the dynamic resistance in the input and output circuits of the amplifiers is controlled. The servo loop is a null seeking loop and the gain of the variable gain amplifiers is controlled in such a manner that the gain of one with respect to the other is inverse.

BRIEF DESCRIPTION OF THE DRAWING

FIG. 1 is a block diagram of the basic control converter and tracking loop;

FIG. 2 is a detailed schematic of the control converters; and

FIG. 3 is a graph illustrating the control converter gain versus control voltages.

DESCRIPTION OF THE PREFERRED EMBODIMENT

With respect to FIG. 1, input signals A and B are coupled into control converters 10 and 11, respectively. The control converters are gain-controlled with a logarithmic gain response. The respective instantaneous gains are G_a and G_b respectively. The outputs of the control converters are subtracted in differencing amplifier 12 and the difference is amplified by an automatic gain controlled (AGC) difference video amplifier 13.

The output of the video amplifier 13 is coupled to an integrator 14 which produces an output D.C. voltage. One output of the integrator 14 is coupled directly back to control converter 11 while the same output is coupled back as an input to control converter 10 through a D.C. inverter 15.

Outputs are taken from the integrator 14 and the D.C. inverter 15 at outputs 16 and 17, corresponding to F_b and F_a respectively, for use in other circuitry.

In operation, the output (F_b) of the pulse integrator 14 is coupled back to control the variable gain amplifier 11. F_b is subtracted from a voltage reference, M, to form the F_a feedback signal which controls the gain of the control converter amplifier 10. The operation is such that the gain of one control converter will be increased while the other is decreased to drive the difference of their outputs to zero. For example, if input signal A is greater than input signal B, the output of the differencing amplifier 12 will be a positive pulse. The integrator output voltage will increase, thus increasing the gain, G_b , of amplifier 11. At the same time F_a decreases, (F_b increases, therefore $M - F_b$ decreases) thus decreasing the gain, G_a , of amplifier 10. This action continues until $G_a \times A$ equals $G_b \times B$. It is important that the gain of the control converters be a logarithmic function of F_a and F_b and temperature stable. Also, it is important that if G_a increases X db, G_b decrease by X db.

The schematic of FIG. 2 illustrates the circuitry associated with the control converter function. Transistors

Q_1 and Q_2 are the variable gain amplifiers 10 and 11 associated with the input signals A and B, respectively. Diodes D_1 through D_8 are the variable gain elements associated with the transistors Q_1 and Q_2 . Transistors Q_3 and Q_4 are constant current drive sources for the variable gain diodes D_1 through D_8 . Transistors Q_5 , Q_6 and Q_7 comprise the difference amplifier 12 of FIG. 1.

The circuit of FIG. 2 operates as follows. The gain of the amplifiers Q_1 and Q_2 (G_a and G_b respectively) depends on the dynamic resistance offered by the diodes D_1 through D_8 . When the integrator voltage (F_b) is equal to the inverter voltage (F_a), the currents through Q_3 and Q_4 are equal and all diodes have the same dynamic resistance. Thus, the gain, G_a , of Q_1 is equal to the gain, G_b , of Q_2 at that time.

If the integrator voltage is increased, the inverter voltage is decreased by the same amount. Thus, more current is passed through Q_3 and less current is passed by Q_4 . The dynamic resistances of diodes D_1 , D_2 , D_5 and D_6 associated with Q_1 are decreased, while the dynamic resistances of diodes D_3 , D_4 , D_7 and D_8 associated with transistor Q_2 are increased.

The gain of amplifiers Q_1 and Q_2 is dependent on the dynamic resistance of the diodes associated therewith. That is, the gain, G_a , of Q_1 is dependent on diodes D_1 , D_2 , D_3 and D_4 . Diodes D_1 and D_2 shunt the collector of transistor Q_1 and diodes D_3 and D_4 shunt the emitter thereof. Therefore, if the dynamic resistances of D_1 and D_2 increase, the gain G_a increases and correspondingly, if the dynamic resistance of diode D_1 and D_2 decreases the gain, G_a , decreases. If the dynamic resistances of the diodes D_3 and D_4 which shunt the emitter of Q_1 increase, the gain decreases. Correspondingly, if the dynamic resistances of D_3 and D_4 decrease, the gain increases.

In that the currents through transistors Q_3 and Q_4 are equal and move equal amounts but opposite in direction, the dynamic resistances of the diodes D_1 through D_4 and D_5 through D_8 vary either to increase or decrease the gains of the associated transistors Q_1 and Q_2 respectively.

For example, if the current through Q_3 increases, the dynamic resistance of diodes D_1 and D_2 decrease. At the same time, the current through Q_4 decreases, thus increasing the dynamic resistance of diodes D_3 and D_4 . At this point, the gain, G_a , of Q_1 will decrease. The diodes associated with transistor Q_2 will be controlled in an inverse manner and therefore the gain, G_b , of Q_2 will increase.

This is so because the current source Q_3 drives the collector coupled diodes of Q_1 (D_1 and D_2) and also the emitter coupled diodes of Q_2 (D_5 and D_6). Transistor Q_4 drives the emitter coupled diodes of Q_1 (D_3 and D_4) and also the collector coupled diodes of Q_2 (D_7 and D_8).

The cross coupling of the diodes ensures that as the gain of one amplifier increases by a given amount, the gain of the other amplifier decreases by the same amount correspondingly.

The cross coupled diodes D_1 through D_8 ensure proper and equal gain changes through varying the gain G_a and G_b of the amplifiers by varying the effective collector and emitter dynamic resistances. This action also ensures that the gain is a logarithmic function of the control voltage. In that the diodes are driven from con-

stant current sources, Q_3 and Q_4 , they are very temperature stable also.

FIG. 3 illustrates graphically, the measured results for the circuit of FIG. 2. As can be seen, the resultant gain of the control converters is nearly linear, as desired. 5

What is claimed is:

1. In a servo loop the improvement comprising:
at least two variable gain amplifiers, each having at least one amplifying component, input circuit coupled to a first terminal of one of said at least one amplifying component, and output circuit, wherein said one of at least one amplifying component of each amplifier is a transistor and said first terminal is the base; and
10
dynamic resistance means operatively connected to each of said at least two variable gain amplifiers for varying the gain thereof, including a first circuit coupled to a second terminal of said one of said at least one amplifying component of a first said amplifier, a second circuit coupled to a third terminal of said one of said at least one amplifying compo-
